UNITED STATES PATENT OFFICE.

LEONARD J. HUSTED, OF LOS ANGELES, CALIFORNIA, ASSIGNOR OF ONE-HALF TO
F. L. ROUNSEVELL, OF LOS ANGELES, CALIFORNIA.

PETROLEUM STILL.

Application filed March 4, 1920, Serial No. 363,182. Renewed December 28, 1925.

The invention relates to apparatus for the distillation of crude petroleum and more particularly to an improved still for distilling crude petroleum and separating gaseous vapors from the residuum, wherein the heating fluid and oil of distillation are circulated through the still in opposite directions, the oil being in continuous process repeatedly spread over hot pipes in which the heating fluid is circulated.

Many petroleum producing localities are at a great distance from an oil refinery with no economical means of transportation and the crude oil cannot be marketed locally without first removing the gasoline, as crude oil is considered dangerous as fuel oil so long as it contains gasoline.

The present invention has provided an improved still for distilling petroleum commonly called crude oil, employing apparatus that can be installed at a small first cost and operated very economically, which may be erected at or near the oil well and moved from time to time, so that the gasoline and coal-oil in isolated localities can be removed from the crude oil and each product find an immediate market, the residuum being used as fuel oil.

With these and other objects in view, the features of the invention are hereinafter set forth, illustrated in the accompanying drawings and more particularly pointed out in the appended claims.

In the drawings:

Fig. 1 is a plan view of a still in which the features of the invention are illustrated.

Fig. 2 is a view of the still in elevation.

Fig. 3 is a broken fragmentary view taken on line 3-3 of Fig. 1.

Fig. 4 is a sectional view taken on line 4-4 of Fig. 3.

Fig. 5 is a sectional view taken on line 5-5 of Fig. 1.

Fig. 6 is a sectional view taken on line 6-6 of Fig. 1.

The shells 1, 2 and 3 are as shown cylindrical, each being provided at each end thereof with a flange 4 by which the shells 1 and 2, and 2 and 3 are secured together forming practically a continuous tube, the pipe header 5 closing one end of the tube and shell 1, while to the opposite end of the tube and shell 3 is secured the receiving chamber 6.

The shells 1 and 2, and 2 and 3 are sepa-

rated by the division wall plates 7, thus forming a closed compartment or chamber of each of the shells, it being understood that any number of the shells 1, 2 and 3 may be secured in this manner and the distillation carried to any desired degree.

The pipes 8 connect to and communicate to the interior of the pipe header 5, and extend through all the division plates 7 to the receiving chamber 6, the ordinary stuffing boxes 9 packing around the pipes 8 and preventing leakage of the oil and gases or vapor from each shell to the adjacent shell, it being understood that the shell 1 is in operation always at a higher temperature than the shell 2, and that shell 2 is a higher temperature than the shell 3, so that the vapor in shell 3 may ignite should it escape to shell 2, and the vapor in shell 2 may ignite should it escape to shell 1. The division plates prevent vapor or residuum passing from one shell to the adjacent shell.

Connected to the shells 1 and 2 are the duplicate spray wheel housings 12, each communicating with the respective shell 80 and provided with the journal boxes 13 in which is journaled the shaft 14, the spray wheel 15 being rigidly mounted on the shaft within the housing, the pulley 16 rigidly mounted on the shaft outside the housing, 85 and the stuffing box 17 preventing leakage of oil or vapor around the shaft.

Each of the spray wheel housings 12 is provided with a trap pipe 12^a connecting to and communicating with the adjacent shell 90 and on the opposite side of the division plate 7.

In the furnace 20 is the heating coil 21, and the burner 22 shown as a means of heating the coil, the pipe 23 connecting from the heating coil to the pipe header 5, so that any heating fluid that may be forced into the heating coil will pass to and through the pipes 8 to the receiving chamber 6.

The pipe 24 connects from the shell 1 to 100 the trap tank 25 below the end 26 of the pipe 27, the pipe 27 connecting from the trap tank to the heating coil 21. The trap tank 25 forms a receiving chamber to collect the residuum as it flows from the shell 1, and this residuum is pumped by the pump 28 to the heating coil 21 and through the pipes 8 to the receiver 6.

The trap tank 25 is provided with the float 29 which closes the end 26 of the pipe 110

27 at all times when the residuum is sufficiently low to allow the float to rest on the pipe, the object of the float being to trap the pipe 24 against the shell 1 so that no air can enter the shell through the pipe, and to prevent vapor from escaping from the shell through the pipe 24.

28 The overflow pipe 30 connects to the trap tank 25 to conduct any surplus residuum 10 from the tank at any time.

29 To the pipe 27 by means of the T fitting 27^a is connected the pipe 31 which is connected to and communicates with the receiving chamber 6, and the valves 32 and 33 are 15 provided in the pipes 27 and 31 respectively so that the pump 28 may draw from the trap tank 25 or the receiver 6 or both simultaneously, although it is preferred to draw from the trap tank only at most times.

30 The receiving chamber 6 is provided with the pipe 34 through which the residuum is drawn after it passes through the shells 1, 2 and 3, trap tank 25, heating coil 21, and pipes 8.

31 The heating coil 35 is positioned in the receiving chamber 6 so that it is during operation of the still submerged in the heating fluid, the lower end protruding to the exterior of the chamber and connected to the pump 36 by which the crude petroleum is supplied to the shell 3, the upper end of the coil passing upwardly from the chamber and entering the shell 3 and preferably provided with the spray holes 37.

32 The shells 1, 2 and 3, receiving chamber 6, trap tank 25, and pipes 23, 24, 27 and 31 are as shown provided with the usual covering to retain heat.

33 The receiving chamber 6 is provided with the door 38 to inspect the pipes 8, more particularly to ascertain when the oil is circulating properly on starting the still in operation at any time, this door also serves as a safety valve for the receiving chamber. The vapor outlet pipe 39 is provided to conduct the vapor from the receiving chamber 6 when the still is started in operation with crude oil as the heating fluid.

34 To operate the still the spray wheels 15 are revolved at high speed by the motor 19 through the cable belts 18, and the petroleum is forced by the pump 36 through the coil 35 and sprayed through the holes 37 onto the pipes 8 in the shell 3. The petroleum falls to the bottom of the shell 3 and flows into the trap pipe 12^a until it reaches the corresponding spray wheel 15. The wheel 15 cuts and beats the petroleum into fine spray and throws it upwardly between and over the pipes 8 when it settles over and around the pipes to the bottom of the shell 2 and flows into the corresponding trap pipe 12^a, the operation being repeated in the shell 1. The petroleum now flows from the shell 1 through the pipe 24 to the trap tank

25, the pump 28 then draws the petroleum from the trap tank through the pipe 27 and forces it to the heating coil 21 and through the pipes 8, it being understood that the valve 33 is as yet closed. When sufficient petroleum has circulated through the coil 35, shells 1, 2 and 3, coil 21 and pipes 8 to fill the receiving chamber 6 to the desired depth, the valve 33 is opened and the valve 32 closed, and the pump 36 discontinued for a time until the heating coil 21 is raised to the desired temperature, it being understood that the shells 1, 2 and 3 will be correspondingly raised in temperature.

36 After the shells are properly heated from the pipes 8, it being understood that any number of shells employed will be correspondingly heated, the valve 33 is closed and the valve 32 opened, and the pump 36 again started, the petroleum being repeatedly circulated through the shells and all the pipes until it reaches the desired temperature, the vapors passing off through the vapor pipe 39. The petroleum in the still now having reached the highest temperature desired, all the vapor releasable at that temperature will have been released and passed through the pipe 39, and only residuum will remain in the still. The pump 36 is again started and continued in operation, forcing the crude petroleum through the coil 35 raising the temperature from the residuum in the receiving chamber 6, and forcing the petroleum through the holes 37 into the shell 3 spraying it over the pipes 8, a portion of the vapor passing off through the pipe 11, the petroleum dripping downwardly over the hot pipes and flowing into the corresponding trap pipe 12^a to the corresponding spray wheel 15 which cuts and beats the petroleum into fine spray and throws it upwardly over the hot pipes 8 in the shell 2, the petroleum dripping downwardly over the pipes and flowing to the corresponding trap pipe 12^a and wheel 15, while the vapor passes off through the corresponding pipe 11. This process is repeated in the shell 1 and the residuum flows to the trap tank 25, while the vapor passes off through the corresponding pipe 11, the pump 28 drawing the residuum from the trap tank and forcing it through the heating coil 21 and pipes 8 to the receiving chamber 6 where it is drawn off through the pipe 34.

37 From the foregoing it will be understood that the crude petroleum is circulated through the shells 3, 2 and 1 and constantly thrown with great force in fine spray over the hot pipes 8, which assists in releasing the vapor gases, the latter passing off through the pipes 11 after which the vapor gases are treated in the usual manner.

38 The residuum flowing from the shell 1 is preferably employed to heat the pipes 8 as it contains a large per cent of the heat re-

quired before entering the coil 21. The residuum is preferable to steam for the reason that it can be raised to the required temperature without generating pressure in the heating coil and pipes, whereas steam would have to be maintained at nearly one thousand pounds pressure per square inch in order to attain and maintain the required temperature.

- 10 The present invention has provided a still wherein the heating fluid is circulated through a continuous straight series of pipes surrounded by a practically continuous tube forming separate chambers through which the petroleum is circulated and repeatedly sprayed by centrifugal force over the hot pipes, the vapors passing off separately from each chamber so that separate condensers can be employed if desired. All the heat 15 given off from the pipes 8 is taken up by the petroleum and resulting vapor except that which is radiated through the shells, none is lost by passing from chamber to chamber as has been the practice. It will 20 be noticed that a portion of the pipes 8 in each shell cannot receive any of the liquid thrown by the wheels 15 and these dry hot pipes maintain the vapor at high temperature until it passes out through the pipes 11, 25 thus preventing the condensation of the vapor in the still.

What I claim is:—

1. In a petroleum still, a series of shells having a common axis, a division wall between the adjacent ends of each companion

pair of said shells, said shells and said division walls secured together, the outer end of one of the end shells of said series of shells being closed, a receiving chamber spread across the end of said shell, the outer 40 end of the opposite end shell of said series of shells being provided with a discharge chamber, a series of pipes leading from said receiving chamber to said discharge chamber, means to deliver a liquid of a high temperature to said receiving chamber and force it through said series of pipes to said discharge chamber, means to spray crude petroleum upwardly against said pipes, means to conduct the gaseous vapor therefrom, and 45 means to drain the residuum from said shells.

2. In a petroleum still, a series of tubular shells arranged with a common axis, said shells being secured together and separated 50 by division walls, a series of pipes extending through said shells longitudinally thereof, means to circulate hot liquid through said series of pipes, means to deliver fluid for distillation to one of said shells adjacent 55 the discharge end of said series of pipes, and a rotary means adjacent each of said remaining shells adapted to spray said fluid of distillation upwardly against and over said series of pipes so that said fluid will drip 60 downwardly over said pipes and prolong the contact therewith in addition to being subject to the beating afforded by the rotary means.

LEMUEL J. HUSTED.
